STEAM FIELD KITCHEN

Richard Morgan Wiles and James Kenneth Wiles,
Adelaide, South Australia, Australia, assignors
to themselves and to John Cuthill Wiles and
Ivor William Wiles, all of Adelaide, South Aus-
tralia, Australia.

Application October 15, 1940, Serial No. 361,230
In Australia November 13, 1939

2 Claims. (Cl. 126—1)

This invention relates to an improved steam field kitchen which can be used as a portable or a mobile unit and which is capable of dealing with large quantities of food.

The object of the invention is to provide an effective apparatus which may be efficiently used whether as a stationary unit or as a transport unit and by means of which edibles may be cooked and water heated with a relatively small quantity of fuel.

A feature of our invention is a special boiler whereby effective steam production is carried out, the boiler being adapted for use in steam cooking. A further feature is the placing of ovens adjacent the boiler to make use of any waste heat from such boiler and also to conserve heat in the boiler when the ovens themselves are being fired. Other features are the arrangement of hot plates, the arrangement of the flues and the arrangement of various other units which will be better understood from the description now to be made with reference to the accompanying drawings in which—

Fig. 1 is a perspective view of a portable unit,
Fig. 2 is a central sectional side elevation of the boiler unit,

Fig. 3 is a section of the boiler unit as on line 3—3 of Fig. 2,

Fig. 4 is a section of same as on line 4—4 of Fig. 2,

Fig. 5 is a section of the oven,

Fig. 6 is a section of one of the steam cookers,

Fig. 7 shows a steam water heater, and

Fig. 8 is a side elevation of a mobile unit.

The steam generator 1 comprises a furnace having beneath it a grate 2 and on each side and over the top of same water tubes which are arranged in sets 3 and 4. The ends of the water tubes communicate with headers 5, 6 and 7 disposed across the front of the boiler, the lower header 5 having the lower ends of the tubes 3, which extend up the side of the furnace, in communication with it, the central header 6 having the lower ends of the sets of tubes 4 in communication with it, and the upper header 7 communicating with the upper ends of all of the water tubes.

The header 7 is connected with a drum 8, the lower part 9 of which acts as a water drum, and the upper part 10 of which acts as a steam drum, the drum being divided by a perforated partition 11. Communication between the lower part 9 of the drum 8 and the header 7 is by means of tubes 12 while a third tube 13 between the header 6 and the drum 8 ensures proper circulation be-

tween that header and the drum. A water inlet 14 communicates with the lower header 5, and this header is in communication with the central header 6 through tubes 15.

5 The boiler unit just described is housed in a shell 16 provided with the necessary fire door, which shell has a portion 17 extending over the top of the boiler drum 8 so that the heat from the furnace after passing between the water tubes 10 and 14 may pass completely around the boiler drum so as to cause some degree of superheating of the steam in the space 10 of the drum. The boiler is supported within the shell by means of stirrups 18, and the shell where necessary may be lagged with asbestos to prevent the escape of heat, such lagging being usually only required within the part 17 of the shell as it is desired to utilise the heat from the sides of the shell to assist in the warming of ovens placed on each 20 side of same.

To enable the water tubes and headers to be disconnected from the steam generator as a unit the two tubes 12 and the tube 13 are provided with unions 19, these unions being of any approved type and permitting quick removal of the water tubes and their replacement by another set if such is required. A spare set of water tubes can thus be provided and, if for any reason the existing set develops a fault, the spare set can 25 be attached in a very short time and the unit is again ready for operation.

The spent gases pass from the shell through a flue 20 the lower end of which is in the form of a collector comprising a chamber 21 and two chambers 22, the former being in communication with the inside of the shell of the boiler and the latter two serving as flues for the ovens placed contiguous to the boiler.

30 The boiler itself is provided with the necessary safety valve 24 and pressure gauge 25 as well as with an outlet pipe 26 having upon it a control valve 27, and is also provided with a forced draught comprising a steam pipe 28 having in it a control valve 29 which pipe is disposed to force 35 a jet of steam through the flue and thus force the draught. A water gauge 30 is provided, while a pump 31 of any usual or approved construction is used to force the required amount of water into the boiler through the inlet pipe 14.

35 Located one on each side of the steam generator are a pair of ovens 33 and 34 each comprising an outer shell 35 and an inner chamber 36, the inner chamber being disposed towards one side of the outer shell to form a space between same 40 in which is a grate 37. The gases from the grate

pass upwardly and over the top of the inner chamber and down the side of same to the inside thereof at which point they pass around a division 38 and to an outlet 39 which communicates with the chamber 22 of the main flue. Each oven is fitted with a fire door 40 and a main door 41 through which access is had to the inner chamber.

It will be appreciated that as the ovens are one on each side of the steam generator they normally take the excess heat from such generator and therefore may be operated very efficiently. 10

Each oven has a hot-plate 42.

Disposed above the ovens 33 and 34 are a pair of subsidiary ovens 43 and 44 which are themselves not provided with a fire grate but take their heat from the steam generator unit and from the ovens 33 and 34 so that they operate on what would otherwise be waste heat.

Disposed along the back of the steam generator and ovens are the steam utensils 45 which each comprises a shell 46 into which leads a steam pipe 47 having at its bottom perforations through which the steam issues into the shell, each utensil being provided with the necessary lid 48 and preferably with a wire receptacle 49 into which the materials to be cooked can be placed.

The unit shown in Fig. 7 comprises a hot water tank 50 having at its top a lid 51 and having projecting into it a steam pipe 52.

The several steam pipes 41 and 52 are placed into communication with the steam outlet 26 from the boiler by means of suitable pipes 54 and hoses 55, such piping having within it the control valves 56 to regulate the flow of steam to the units as required. The unit constructed as described herein can be used both as a mobile or a portable arrangement in that the various parts can be readily dismantled one from the other and are then suitable for transport purposes. The particular grouping according to which the steam generator 1 is disposed between the ovens 33 and 34, and the steam utensils 45 and tank 50 are disposed adjacent the generator and the ovens, results in a considerable saving in fuel in that as said the waste heat from the steam generator serves to heat the ovens and also in that the ovens when they are in use serve to maintain the heat of the steam generator. A heat exchange also takes place between the steam utensils and the ovens and steam generator so that at all times a very effective use is made of the heat generated at any point.

According to the embodiment shown in Fig. 8 the unit is placed upon a trailer which comprises a suitable frame 60 supported upon wheels 61 and including side members 62 and a roof 63 of any approved construction.

In this unit an oven 33 is placed adjacent a 60

steam generator 1, with a water heater 50 in the form of a steam heated storage tank placed at the back of the unit preferably with a cold water tank adjacent same. The steam utensils 45 are placed along one side of the unit and a fuel bin 64 is situated at the rear of the unit. The fuel bin preferably extends partway across the unit only and the space adjacent same serves to hold a spare wheel and a spare set of tubes for the steam generator. The steam generator is provided with a pump 31, and the flue 20 of the boiler projects through the roof 63.

The sides of the unit are preferably enclosed which may be achieved either by using metal walls or shutters or by using canvas or the like, or a combination of these may be used or metal sides with a front and back closure of detachable canvas.

The steam utensils 45 are as said disposed along one side of the unit and the opposite side thereof is provided with a table 65 which projects out but leaves sufficient room for the cook or attendants to walk to the fuel bin 64 at the rear of the unit and to generally move about in their duties. A small auxiliary fuel storage space 66 can conveniently be provided adjacent the steam generator unit. The unit is provided with an entrance 67 which is preferably provided with a door of any suitable construction such as a slideable door, and a hinged step may also be provided in association with such door.

What we claim is:

35 1. An improved steam field kitchen comprising a casing having sides and end walls, a heating means, a drum in the upper portion thereof, the lower portion forming a chamber adapted to contain said heating means, water tubes located between the heating means and the drum, ovens located in abutting and heat interchanging relation to the sides of said casing, heating means located within each oven, a flue extending from the casing, a flue extending from each oven and a common outlet flue connecting said flues.

15 2. An improved steam field kitchen comprising
a casing having sides and end walls, a heating
means, a drum in the upper portion thereof,
the lower portion forming a chamber adapted to
contain said heating means, water tubes located
0 between the heating means and the drum, ovens
located in abutting and heat interchanging re-
lation to the sides of said casing, heating means
located within each oven, a flue extending from
the casing, a flue extending from each oven, a
5 common outlet flue connecting said flues, and
steam pipes connected to said drum and adapted
to be attached to steam utensils.
